SUCTION CLEANER

Peter W. Cherry, Monroe, and Carl N. Johnson,
Stratford, Conn., assignors to General Electric
Company, a corporation of New York

Application April 13, 1951, Serial No. 14,821

Term of patent 14 years

(Cl. D9—2)

To all whom it may concern:

Be it known that we, Peter W. Cherry, a citizen of the United States, residing at Monroe, in the county of Fairfield, Connecticut, and Carl N. Johnson, a citizen of the United States, residing at Stratford, in the county of Fairfield, Connecticut, have jointly invented a new, original, and ornamental Design for Suction Cleaner of which the following is a specification, reference being made to the accompanying drawing, forming part thereof.

In the drawing, Fig. 1 is a perspective view of one side of the cleaner, with the carrying handle in one position, and Fig. 2 is a perspective view of the opposite side of the cleaner, with the carrying handle in another position.

We claim:

The ornamental design for a suction cleaner, substantially as shown and described.

PETER W. CHERRY.
CARL N. JOHNSON.
